Primary Examiner — Michael A Pratt(74) *Attorney, Agent, or Firm* — Stolowitz Ford Cowger LLP(57) **CLAIM**

An ornamental design for the firearm charging handle, as shown and described.

DESCRIPTION

FIG. 1 is a top view of an embodiment of my firearm charging handle; and,

FIG. 2 is an enlarged top view of the firearm charging handle shown in FIG. 1.

The broken lines are included for the purpose of illustrating the environment and form no part of the claimed design.

1 Claim, 2 Drawing Sheets(56)
